(57) **CLAIM**

The ornamental design for a sous vide immersion circulator, substantially as shown and described.

DESCRIPTION

FIG. 1 is a side perspective view of a sous vide immersion circulator showing our new design.

FIG. 2 is a front view.

FIG. 3 is a back view.

FIG. 4 is a left side view.

FIG. 5 is a right side view.

FIG. 6 is a top view; and,

FIG. 7 is a bottom view.

The broken lines in the drawings and the areas within them depict portions of the sous vide immersion circulator that form no part of the claimed design.

The shading lines in FIG. 6 indicate a transparent surface.

1 Claim, 5 Drawing Sheets
